UNITED STATES PATENT OFFICE.

JOSEPH M. COFFEY, OF ELIZABETH, NEW JERSEY, ASSIGNOR TO CHAMBERS VALVE COMPANY, OF NEW YORK, N. Y., A CORPORATION OF NEW YORK.

THROTTLE-BOX.

1,289,396.

Specification of Letters Patent.

Patented Dec. 31, 1918.

Application filed February 12, 1918. Serial No. 216,835.

To all whom it may concern:

Be it known that I, JOSEPH M. COFFEY, a citizen of the United States, residing at Elizabeth, in the county of Union and State 5 of New Jersey, have invented certain new and useful Improvements in Throttle-Boxes, of which the following is a specification.

This invention relates to improvements in throttle boxes and more particularly to 10 throttle boxes especially adapted for use on locomotive steam boilers.

One of the objects of the present invention is to provide an improved throttle box of simple and practical construction having 15 relatively few parts which may be inexpensively manufactured and assembled. A further object is to provide a box of the above general character with its parts so positioned and arranged that it may be rigidly 20 attached or secured to the dome, thereby to prevent leakage. A further object is to provide a throttle box of the above general character in which the parts are so supported as to permit an easy and free work- 25 ing of the valve under all conditions.

Other objects will be in part obvious from the annexed drawings and in part indicated in connection therewith by the following analysis of this invention.

30 This invention accordingly consists in the several steps and the relation of each step to each of the others both individually and in combination; all as more completely outlined herein.

35 To enable others skilled in the art so fully to comprehend the underlying features thereof that they may embody the same by the numerous modifications in structure and relation contemplated by this invention, 40 drawings depicting preferred forms have been annexed as a part of this disclosure, and in such drawings, like characters of reference denote corresponding parts throughout all the views, of which:—

45 Figure 1 is a plan view of the throttle box and associated parts with the dome in section;

Fig. 2 is an elevational view partly in section of the mechanism shown in Fig. 1,

50 Fig. 3 is a detail plan view showing a

modification applicable to the structure disclosed in Fig. 1.

Referring now to the drawings in detail, 5 denotes the upper part of the boiler shell to which is secured a steam dome 6, both of well known construction. Leading from the steam dome to the cylinders is a dry pipe 7 connected at one end with an elbow 8 supporting a stand pipe 9 for the throttle box. The upper part 10 is secured thereto as by 60 means of a U-bolt 11 and is also provided with a laterally projecting lug 13 adapted to rest upon the upper side of a ledge 14 and be secured thereto by means of bolts passing through registering openings 15. From 65 Fig. 1, it will be seen that the elbow 8 supporting the box 10 is curved to bring the same more closely adjacent the wall of the steam dome 6. This throttle box is provided with any desired type of throttle valve 70 16 and balancing piston 17, as herein shown, although it is of course to be understood that other types of valves may be used with the mechanism hereinafter described, if so desired. This throttle valve is adapted to 75 be actuated by means of a laterally extending shaft 17' passing through the side of the steam dome 6 and provided at its end with a crank arm 18, the end of which is adapted to be connected by means of a pull rod, or 80 the like, extending rearwardly to the throttle lever in the cab in the usual way.

The present invention resides more particularly in the provision of means surrounding this shaft and connected with the 85 steam dome designed to act both as a protector for the actuating shaft 17' and also a stuffing box to prevent leakage around the point where it passes through the wall of the steam dome. The upper part 10 of the 90 throttle box is accordingly provided with an integrally formed laterally projecting sleeve 20 having a flange member 21 or integrally formed plate which can be calked or electrically welded at 22, if desired, to the inner 95 surface of the steam dome. It is preferred to use a copper gasket 19 adapted to be clamped between the flange and liner 22 by means of studs 23. The sleeve 20 projects beyond this plate 21, thereby providing an 100

extension 24 projecting beyond the outer surface of the dome 6 which acts as a stuffing box.

It is preferred to use a gland 25 on the outside, which is held in place by studs 26 to prevent leakage of steam from the dome to the atmosphere. This simple and practical combination of parts eliminates all steam leakage and may be easily and quickly installed. It also has the desirable feature in that it tends toward keeping the parts in line, thus producing a very easy working valve. It is, of course, to be understood that the interior of these parts are provided with a packing ring 27, lubricating and drainage means 28 and 30, substantially as shown.

In Fig. 3, there is shown a slight modification in which a member 31 corresponding to the flange 21 is curved transversely to conform more closely to the inner surface of the steam dome and is provided with a peripheral lip 32 adapted to be electrically welded to the inner surface of the dome 6 rather than to be bolted thereto, as shown in Figs. 1 and 2. The construction is otherwise substantially the same.

The first construction, however, is believed to be preferable for certain reasons inasmuch as the joints can be more easily broken and the throttle removed when it is desired to substitute or replace worn or broken parts.

It is believed from the above description that the method of arrangement and operation of the parts of the invention herein disclosed will be clear to those skilled in the art, and a further statement thereof is unnecessary.

The invention is of simple and practical construction, having relatively few parts and is believed to accomplish, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

I claim:

1. In a device of the character described, in combination, a steam dome, a throttle box therein supported from said dome, said throttle box having a valve and actuating shaft, and an integrally formed sleeve and stuffing box for said shaft extending between the dome and the box.

2. In a device of the character described,

in combination, a throttle box having a 65 valve and actuating shaft, an integrally formed sleeve and stuffing box for said shaft, and means for rigidly securing said parts directly to the inner wall of the steam dome.

3. In a device of the character described, in combination, a throttle box having a valve and actuating shaft, an integrally formed member surrounding said shaft and adapted to have a rigid connection directly 75 with the inner wall of a steam dome.

4. In a device of the character described, in combination, a throttle box having a valve and actuating shaft, a combined sleeve and stuffing box surrounding said shaft and integrally connected with said box.

5. In a device of the character described, in combination, a dome, a throttle box containing a valve and adapted to be connected with a dry pipe, an actuating shaft extending from said box out through the side of the dome, and a combined covering and stuffing box for said shaft integrally formed with said throttle box.

6. In a device of the character described, in combination, a steam dome, a throttle box positioned within said dome and provided with a valve, an operating shaft extending from said box out through the side of the dome, an integrally formed sleeve and stuffing box for said shaft, and means for securing said box to the dome adjacent the point where said shaft passes through said dome.

7. In a device of the character described, in combination, a steam dome, a throttle box positioned within said dome and provided with a valve, an operating shaft extending from said box out through the side of the dome, an integrally formed sleeve and stuffing box for said shaft, and coating means on the dome and box whereby the box is supported from said dome.

8. In a device of the character described, in combination, a steam dome, a throttle box 110 within said dome adapted to be connected with the dry pipe, a valve in said box, an actuating shaft for said valve extending out through the wall of said dome and adapted to be connected with the throttle lever, an 115 integrally formed sleeve and stuffing box for said shaft interposed between said dome and box, and means for rigidly securing the stuffing box portion of said sleeve to the inner wall of said dome.

9. In a device of the character described, in combination, a steam dome, a throttle box 125 within said dome adapted to be connected with the dry pipe, a valve in said box, an actuating shaft for said valve extending out through the wall of said dome and adapted to be connected with the throttle lever, an integrally formed sleeve and stuffing box for

said shaft interposed between said dome and box, means for rigidly securing the stuffing box portion of said sleeve to the inner wall of said dome, said means including a flange, 5 a gasket interposed between the flange and inner surface of the dome and means for securing said parts in fixed position.

In testimony whereof I affix my signature in presence of two witnesses.

JOSEPH M. COFFEY.
